UNITED STATES PATENT OFFICE.

HARRY T. BRADLEY AND FRANK JACOBI, OF NEWARK, NEW JERSEY.

COLLAPSIBLE HAMPER.

Application filed May 12, 1925. Serial No. 29,699.

This invention relates to that class of containers known as hampers, and more particularly to types having folding or collapsible walls.

- 5 One of the objects is to provide a hamper, the side and end walls of which consist of interconnected jointed wire frames and means combined therewith whereby these elements are normally held erect in operative position.
- 10 A further feature is in the provision of means to retain the walls when folded over the bottom so that the hamper may be conveniently stored or transported as a compact unit, when not required for use.
- 15 Another aim is to provide a strong rectangular hamper structure, having a woven textile covering, and resting on skids provided with castors or equivalent members, permitting the structure to be readily moved
- 20 over level surfaces, even when heavily loaded to capacity.

These and other pertinent objects are accomplished by the novel design, construction and combination of parts hereinafter described and shown in the accompanying drawings, forming a material part of this disclosure, and in which:

Figure 1 is a perspective view of a hamper made in accordance with the invention, looking from the lower side, the fabric casing being partially broken away from the skeleton frame.

Figure 2 is a bottom plan view of the same.

Figure 3 is a top plan view thereof, the frame being shown in a folded position.

Figure 4 is an end elevational view drawn to an enlarged scale.

Figure 5 is a fragmentary sectional view 40 looking on line 5-5 of Figure 3.

The base of the hamper is composed of a pair of rectangular skids 10 having their ends partially bevelled upwardly and provided on their lower surfaces with antifriction castor elements 11 of any preferred type to rest upon a floor, rendering the hamper easy to move thereover.

Secured rigidly on the upper surfaces of the skids, adjacent their ends, are metal cross bars 12 and at the center is a similar cross bar 13, these bars retaining the skids in spaced relation.

The bars 12 are sheared, as at 14, inwardly from both edges, near their ends, to produce 55 pairs of pads 15, through which the fastening means are passed, and intermediate the

pads are sockets 16, their upper surfaces being level with the main portions of the bars which are raised slightly above the intermediate bar 13.

Said intermediate bar is slit lengthwise at each end to produce three prongs, the middle prongs being bent at right angles upwardly to constitute stops 17, the purpose of which will become apparent.

The outer prongs are bent over upon the surface of the bar to form sockets 18, their terminals extending inwardly to constitute pads through which the securing means pass.

Pivotedly engaged in the sockets 18 are the out-turned ends of rods 20, normally extending in doubled relation to the top of the structure, when raised vertically in contact with the stops 17, and are bent to present pairs of opposed, integrally connected eyes 21.

Loosely engaged in the eyes 21 are closed loops formed at one end of links 22, their other ends having similarly closed loops engaged in eyes 23 formed by coiling rods having transverse members 24 and right angularly extending members 25.

Said members 25, constituting the corner posts of the structure when extended vertically, are inbent at the lower portions to engage in the sockets 16, passing below the bars 12 to terminate in closed loops 26.

Engaged in the loops 26 are the eyes of couplings 27 set in one of the ends of coiled tension springs 28, the other ends of the springs having similar couplings 29 connected in paired relation on each side of the structure by links 30.

The effect of the springs 28 is communicated to the corner elements 25, causing them to rotate on the axis of the sockets 16, and, due to the leverage obtained by the elements 26, the corner elements are forcibly raised into a normally vertical position.

It is to be noted that the elements 25 swing in planes lengthwise of the structure and that the central support elements 20 are pivoted to move in a transverse plane, permitting them to be closely folded over the intermediate bar 13, at which time the links 22 will be positioned substantially parallel with them and are overlaid by the elements 24, thus folding compactly.

Upon raising the elements 25, motion is transmitted through the links 22 to the elements 20, causing them also to assume an erect position, the links 22 moving through

a laterally angular path in closing or opening the hamper.

In order to retain the parts when in a collapsed or folded position, a wire 31 has 5 its extending ends secured to the inner side of one of the rod members 24, the wire being bent to present a doubled hook 32, adapted to engage in the bight 33 of a similar wire having its ends 34 secured to the opposite rod member, these elements being sufficiently resilient to permit of engagement or separation at will, thereby securing the frame members or releasing them as may be desired.

15 It is to be understood that the skeleton frame thus provided is equipped with a covering, generally designated by the numeral 35, this covering being preferably of a strong woven textile fabric, as canvas, duck 20 or the like, hemmed at its edges and secured to the several frame elements by stitching as shown.

As the covering is highly flexible, it presents no impediment to folding the structure or prevent use of the latching device, the elements 32 and 33 extending through in 25 a manner readily accessible for operation.

While a certain preferred embodiment of this device has been shown and described, it 30 will be understood that changes in the form, arrangement, proportion, size and details thereof may be made without departing from the scope of the invention as defined in the appended claims.

35 Having thus described our invention, what we claim as new and desire to secure by Letters Patent, is:—

1. A collapsible hamper comprising a pair of spaced skids of rectangular cross section 40 provided with bevelled ends having end and intermediate cross bars, a frame composed of corner, side and rim members interconnected by integral hooks and eyes at their outer ends and simultaneously foldable over 45 said skids, all of the corner and side members having permanently hinged connections with the skids and presenting a regular rectangular structure when erect, and a woven covering at the bottom, sides and ends of 50 the structure above the skids and cross bars thereof.

2. A collapsible hamper comprising a pair of spaced skids of rectangular cross section 55 provided with bevelled ends having end and intermediate cross bars, a frame composed of loosely connected corner and side members, having hooks and eyes at their outer ends, said side members being foldable laterally inward and said corner members folding longitudinally thereover, links connecting 60 the corner and side members to constitute rim members when the corner members are erect and to effect simultaneous folding of said corner and side members, stops on 65 the intermediate cross bar limiting the out-

ward movement of said side members, and hinge elements positively engaging said corner and side members to the skids.

3. A collapsible hamper comprising a pair of spaced skids having end and intermediate cross bars, glide castors on the under-surface of said skids, rods hingedly engaged at the ends of the end bars and connected in pairs at their outer extremities to extend across the ends of the hamper, other rods 70 hingedly engaged at the ends of the intermediate bar, stops for the last named rods, links loosely connecting the upper ends of the last named rods with the corner members to permit inward folding of the same, 80 and a flexible covering secured to said members to form a rectangular container.

4. A collapsible hamper comprising a pair of spaced skids rigidly connected in spaced relation, a frame composed of end and side members hingedly connected to said skids, said side members being foldable transversely over the skids and said end members longitudinally thereover and being interconnected with said side members for simultaneous folding movement, resilient means for normally raising and retaining all of said members in an erect position, and means for securing said members when in a folded position.

5. A collapsible hamper comprising a pair of spaced skids rigidly connected in spaced relation, a frame composed of end and side members hingedly connected to said skids, said side members being foldable transversely over the skids and said end members being foldable inwardly thereover, links connecting the side and end members, said links constituting parts of the rim of the structure, a flexible fabric covering secured to the rim, side and end members, said end members having downwardly extending extremities, and tension springs engaging between the extremities at each side of the frame, said springs acting to erect the end members and exert a similar effect upon the side members through said links.

6. A collapsible hamper comprising a pair of spaced skids rigidly connected in spaced relation, a frame composed of end and side members hingedly connected to said skids, said side members being foldable transversely over the skids and said end members being foldable inwardly, links connecting the side and end members at the sides of the frame, projections extending from the end members below the plane of their hinges, springs connecting said projections at the frame sides to exert a raising effect, a flexible covering for the frame, and a hook and keeper device fixed on the respective end members of the frame to extend through said casing for retaining said members when in a collapsed position.

7. A collapsible hamper comprising a pair

of skids, means on said skids to facilitate movement, a frame composed of interconnected side and end members to constitute a rectangular structure, said members being hingedly connected to the skids and simultaneously foldable inwardly, tension springs adjacent said skids to exert a raising effect

on said members whereby they are normally held erect, means for holding said members when collapsed, and a flexible covering secured to said members to envelope the frame. 10
